UNITED STATES PATENT OFFICE.

HERMAN ALWES, OF EUREKA SPRINGS, ARKANSAS.

BERRY-BOX.

No. 889,651.

Specification of Letters Patent.

Patented June 2, 1908.

Application filed April 2, 1907. Serial No. 366,024.

To all whom it may concern:

Be it known that I, HERMAN ALWES, a citizen of the United States, residing at Eureka Springs, in the county of Carroll and 5 State of Arkansas, have invented new and useful Improvements in Berry-Boxes, of which the following is a specification.

This invention relates to that class of boxes and receptacles which are commonly 10 used for the transportation of small fruit, and which are generally known as berry boxes, and it has particular reference to that class of berry boxes which comprise a body or wall formed of a strip of material, such as 15 veneer, pasteboard or the like, bent into shape and provided with notches adapted for the support of a bottom member, the corners of which project through such notches.

20 The present invention has for its object to provide improved means for securing together the overlapping ends of the strip constituting the wall or body of the berry box; and further objects of the invention are to 25 simplify and improve the construction and operation of said fastening means.

With these and other ends in view which will readily appear as the nature of the invention is better understood, the same consists 30 in the improved construction and novel arrangement and combination of parts which will be hereinafter fully described and particularly pointed out in the claims.

In the drawing, Figure 1 is a perspective 35 view of a berry box, the overlapping ends of the body or wall of which are secured together by one form of the improved fastening device. Fig. 2 is a sectional view taken on the plane indicated by the line 2—2 in Fig. 1.

40 Corresponding parts in the several figures are denoted by like characters of reference.

In the illustrated form of the invention, the overlapping ends 1—2 of the side wall or body of the berry box are provided with 45 slots 3—3 and 4—4 disposed in registry for alinement with each other.

The fastening member shown is composed of a strip 5 of flexible sheet metal, which is provided intermediate the ends thereof with 50 bent or doubled portions 6—6 which are

spaced apart a distance equal to the distance between the slots 3—3 or 4—4 in the overlapping ends 1—2 of the wall or body of the box; the doubled portions 6—6 of the strip are inserted through the slots 3—3 and 4—4 55 after said slots have been placed in registry with each other, and the extremities of the double portions are then bent down flat adjacent to the inner flap 2 of the wall or body, as shown at 7—7, while the terminal ends of 60 the strip 5 are bent adjacent to the upper and lower edges of the outer flap 1 of the wall or body and inserted between the flaps 1—2, as will be clearly seen in Fig. 2 of the drawings. In this manner, the free ends of the 65 strip will be protected, there being no exposed ends liable to catch or become engaged with adjacent boxes or other material.

Instead of constructing the fastening members of strips of sheet metal, as hereinbefore described, the said fastening members may be bent from strands of wire, in substantially the shape indicated as will be very readily understood.

From the foregoing description taken in 75 connection with the drawings hereto annexed, the operation and advantages of this invention will be readily understood. The construction is simple, inexpensive and thoroughly efficient for the purposes for which it 80 is provided.

Having thus fully described the invention, what I claim as new is:—

In a berry box, a wall or body having overlapping end flaps provided with registering 85 slots near their upper and lower edges, in combination with a flexible metallic fastening member provided intermediate its ends with double portions extended through the registering slots and bent down upon the adjacent flap, the terminal ends of the fastening member being bent adjacent to the edges of the flaps and inserted between the latter.

In testimony whereof, I affix my signature in presence of two witnesses.

HERMAN ALWES.
